ABSTRACT

Device for the wet treatment of packed and similar textile materials, comprising a hermetically locked enclosure, containing the treatment bath for the material, and the interior of which is divided into two chambers. One of these chambers communicates with the interior of the perforated cores which carry the packed material to be treated and their perforated tubular supports and the other chamber communicates with the outside of these cores. Both these chambers are separated by a volumetric alternating treatment bath impelling mechanism, this mechanism is of a type made up of a piston, a membrane pump or rotating pump. Said alternating treatment bath impelling mechanism impels, during every one of its to and fro strokes a part of the treatment bath and compels it to pass through the textile material or, respectively, from the inside of same towards the outside and from the outside towards the inside. The treatment bath volume which each time flows through the textile matter from the outside towards the inside of same is being kept enclosed in said chamber which communicates with the inside of the perforated tubular supports which support the textile material, and is at same time kept separated from the remainder of the total treatment bath volume which has not passed through the textile matter.

**DEVICE FOR THE WET TREATMENT OF PACKED
AND SIMILAR TEXTILE MATERIALS**

This invention refers to a device for the wet treatment of textile and other similar filiform matters, and more strictly speaking, it has for its subject an improved autoclave capable of being applied in the textile industry, the purpose of which is to subject to the action of the various treatment baths the textile matters which find themselves in their various processing stages; it is specially meant for the dyeing of raw, spun or woven fabrics; this autoclave offers substantial, mainly technical, advantages in comparison to those used heretofore.

According to the classic arrangement of such autoclaves, the filiform or textile matter, be it in the raw stage, or in a spun or woven shape, is suitably "packed" inside the autoclave and the treatment bath or baths are being impelled through them, whereby this form of circulation within the normal autoclaves is being achieved by means of a pump or propeller.

This usual system or propulsion of the treatment bath by means of a pump offers several disadvantages. Firstly, it does not allow to carry out a perfect treatment of the textile matter, for the functioning of a given pump in general cannot adapted to the flow and pressure conditions required by the fluidynamic characteristics of a given textile package, what frequently causes the treatment to be carried out at a higher pressure than the right one, thereby causing the hardening of the package, solution leakage and other disadvantages.

On the other hand, the uniformity of the wet treatment of the packed textile matter, specially during the dyeing process, depends, among the other factors, of the number of times the circulation flow of the treatment fluid is reverted through the textile matter, thus said uniformity improves considerably along with the increase of said number of reversals, but since the pump's own inertia does not allow to revert its movement at a high frequency, it results that a relatively considerable time is needed to perform the necessary reversals of the treatment bath's direction of flow.

Should this wet treatment consist in a dyeing process, it is, furthermore, utmost essential to have a treatment bath temperature control, for the temperature has an utmost marked effect on the absorption velocity of dyestuffs by textile matters and on the total quantity of dyestuffs absorbed by the fiber at the end of the dyeing process.

If only the kinetic aspects of the dyeing process, which on the other hand is the most important operation in the dyeing process from the industrial standpoint, are considered, the connection between the absorption velocity and the temperature (see "The Physical Chemistry of Dyeing," by T. Vickerstaff, 2nd edition, page 160) is

$$\ln K_T = K_o - (E/RT)$$

or

$$K_T = K_o \cdot e^{-(E/RT)}$$

where

K_T = Reaction velocity constant at the temperature T

K_o = Constant term

E = Activation energy

R = Gas constant

T = Temperature of the dyeing stuff.

As it may be appreciated, the absorption velocity constant K_T varies exponentially with the temperature so that when the temperature increases the absorption velocity increases notably. The value of this increment depends from the momentary affinity towards the fiber, and in great affinity dyeing systems, for instance, cationic dyeing stuffs and polyacrylonitrile fibers, temperature differences of 1°C mean absorption velocity differences of the 30 percent order, what causes these dyeing systems to be extraordinarily sensible to temperature variations.

Thus it is understood that in the dyeing process of a packed textile matter, where the direction of circulation of the dyeing solution changes from the inside towards the outside and from the outside towards the inside, it is necessary that the temperature of the solution in both flow directions be always the same in order that the absorption of the dyeing stuff be the same inside as outside of the packed textile material in order to obtain a uniform dyeing.

Such conditions are unattainable with the usual autoclaves where the heat exchangers are connected in the circuit where the treatment bath flows in both directions and the various heat losses which the treatment bath suffers when circulating in the one or other direction cannot be made up for.

By means of the autoclave which is the subject of this application these advantages can be solved, whereby the treatment bath is enabled to flow through the textile matter following a very easily variable reciprocating movement of high frequency and according to the pressure characteristics at a constant flow of liquor per unit time, which depend only from the structure of the packed textile matter, which is thus subjected to the necessary minimum pressure to overcome the textile material packet's resistance which is a function of the flow of the liquor which passes through it. Furthermore, this device allows to separately heat the treatment bath flowing from the inside towards the outside of the textile matter packet and the portion of the treatment bath which flows from the outside towards the inside of the packet, whereby a wide range of variation of the working conditions may be obtained which considerably increases its application possibilities.

Essentially, this device is made up by an autoclave container, consequently it is provided with a tight look, containing the treatment bath, and comprises a volumetric reciprocating mechanism impelling said treatment bath from a chamber which communicates with the drilled supports or material carriers which carry the materials to be treated, so that the reciprocating movement of said mechanism impels a portion of the treatment bath during the upward stroke as well as during the downward stroke and compels it to flow through the textile matter in the one and opposite direction, whereby at the same time a separation between the two cited chambers is being established, what is the reason why the amount of the treatment bath flowing through the textile matter from its outside towards the inside of same finds itself confined independently from the total treatment bath volume which does not flow through it; this separation allows to independently handle each one of the portions into which is divided the total bath volume, in order to heat or cool them or add products to them; for this purpose the above cited chambers of

the autoclave itself are provided with independently controllable heat exchangers as well as with the appropriate means for the introduction of additional products.

Above mentioned treatment bath impelling mechanism may be located within the autoclave's inner space, or outside same and connected with the autoclave's inner space and the material carriers inside same by the appropriate conduits.

On the other hand, the active organ of this treatment bath impelling mechanism may consist of a piston, membrane pump or radial rotary pump or any other contrivance with a reciprocating movement capable of acting in its two opposite strokes.

Other advantages and features of the device will be explained in the following specification hereinafter described, which refers to enclosed drawings and is only given as an example of an embodiment of the invention with no feature that might limit the scope of the invention.

FIG. 1 is a diagram explaining the operating conditions of the usual autoclaves, where the circulation of the treatment bath is obtained by means of a pump.

FIG. 2 is a diagram similar to above, but the impelling of the treatment bath is made by a volumetric mechanism according to the invention.

FIG. 3 is a sketch showing a lengthwise section through a textile package showing the flow of the fluid through same.

FIG. 4 is a plan view corresponding to the foregoing figure.

FIG. 5 is a diagram showing the variations of the concentration of the product affine to the fabric according to the distinct zones of the packet, as a function of time, which take place in the treatments by means of the usual devices.

FIG. 6 is a diagram similar to the foregoing one, corresponding to the treatment by means of the device which is the subject of this invention.

FIG. 7 is a schematic cutaway of an embodiment of the device which is the subject of this application, in which the impelling mechanism is housed inside the container of the autoclave itself.

FIGS. 8 and 9 are views similar to that of FIG. 7, which show two variants in which different typed of the treatment bath impelling mechanism are used.

FIGS. 10, 11 and 12 show the same number of variants of the device, each one provided with the treatment bath impelling mechanism as shown in FIGS. 7, 8 and 9, but this mechanism being located outside the autoclave.

One of the main features of this device, which is the subject of this invention, lies in that it is provided with a volumetric device for the propulsion of the treatment bath through the textile packet, this device having a reciprocating movement, the features of which make it essentially different, both in regard to construction and to operation, from the known autoclaves in which the propulsion of the treatment bath is made by means of a pump or screw, whereby the difference of operation is to be seen from the diagrams shown in FIGS. 1 and 2.

In FIG. 1 the connection of the operating features of a determined pump, i.e., the pressure P and the flow per unit time Q , is in general shown by a curve such as curve M. On the other hand, each textile packet has its own fluodynamic characteristics so that when a liquid

passes through it it offers a resistance to the passage of the same which depends on the permeability and flow per unit time which passes through it, these characteristics being connected with each other by an exponential function; in said FIG. 1 are shown the curves E_1 and E_2 corresponding to two textile packets of different permeability.

In a usual autoclave, the operating point of the treatment bath impelling pump is determined by the intersection of the curve M with that of the corresponding textile packet, i.e., by the points A_1 and A_2 for the textile packets E_1 and E_2 , and they determine the flow of liquid per unit time Q_1 and Q_2 , respectively, which passes through the textile matter. Thus it is to be seen that the flow of liquid per unit time depends on the pump type used and on the features of the textile packet. Consequently, should one be interested in having a determined textile packet (E_1) working in one point of its curve such as C with the characteristics P_c and Q_c , this would not be possible for the pump (M) is unable to work in such conditions, but the system would settle in a point D on curve M for which the flow per unit time Q_c corresponds to the pressure P_d , what would entail a change of the permeability of the textile packet according to E_1 because the pump would work at a higher pressure, with the drawbacks which result from it.

On the other hand, if the propulsion of the liquor is being made, according to the invention, by means of a reciprocating mechanism, the value of the pressure depends on the resistance offered by the textile packet to the passage of the liquor in the way shown in FIG. 2, i.e., for two textile packets represented by the curves E_1 and E_2 the working pressures will be P_1 and P_2 , respectively, for a determined flow of liquor per unit time Q_1 the pressures depend on the nature of the textile packets but not on the features of the treatment bath impelling mechanism.

These pressures P_1 and P_2 are the pressures strictly needed for the liquid to pass through the textile matter, so that this is not subjected to an excess of working pressure as it is the case when the liquid is impelled by a pump, and, consequently, the textile packet is not being deformed, what fact means an important advantage over the usual system, for each deformation causes an unequal treatment and produces anomalies in the results.

If, due to the requirements of the operating process it is considered necessary to increase or decrease the flow per unit time, this variation may be obtained by speeding up or slowing down the movement of the reciprocating mechanism, resulting, then, the flows per unit time Q_2 and Q_3 , respectively, in this event the textile packet will be subjected to different pressures. This possibility also means an advantage over the propulsion of the treatment bath by means of a pump, for one is in the position to vary the flow per unit time for a determined textile packet, which is not so easily possible when the impelling mechanism is a pump.

The consequence of the constructive mode and of the operation of the reciprocating mechanism is the possibility to change, using a high frequency of the piston strokes, the direction of flow of the solution through the textile packet. The possibility to quickly vary the direction of flow is of the highest importance

in order to obtain a uniform dyeing of the inner and outer layers of a textile packet treated with circulating solutions flowing through it; this is based on the following:

When a textile packet, such as shown in FIGS. 3 and 4, is subjected to a treatment in which affinity effects between the fabric and the component products of the treatment solution (such as dyeing stuffs, chemical products, etc.) are involved, selective absorption of the product effects are produced in the measure the treatment passes through the fabric.

If we call Q the flow of the treatment solution per unit time passing through the textile packet sketched in those figures, S_i and S_e the inner and outer surfaces of the textile packet normal to the direction of flow of the solution, X_i and X_e the concentration of the product on to the fiber at the time the solution is getting in contact with the inner and outer surface of the textile packet, respectively, and C_i and C_e the quantity of product on to the inner and outer surface of the textile packet, accumulated during the time T , K being equal to the proportionality constant, it will be, when the flow of the treatment solution is from the inside towards the outside of the textile packet:

$$C_i = K(Q \cdot X_i / S_i) \cdot T; C_e = K(Q \cdot X_e / S_e) \cdot T;$$

Since S_e is greater than S_i and X_i is greater than X_e due to the affinity effect, it is easily understood that C_i is greater than C_e and if the process would go on for ever in this direction there would be an accumulation of the effective product in the inside of the textile packet, thereby producing an uneven treatment of the same. If the flow of the treatment solution is from the outside towards the inside, X_e is greater than X_i , what seems to counteract the effect that S_e is greater than S_i for a determined value of X_e and X_i , but since these concentrations vary during the process, the values of C_i and C_e never would be equal. Generally speaking, it can be said that the flow of the treatment solution from the inside towards the outside causes treatments with a greater accumulation of the product in the inner zone, and that the flow from the outside towards the inside causes treatments with a greater accumulation of the product in the outer zone, although this accumulation is not as marked as in the case of the flow inside-outside. From this it is to be inferred that there is need to change directions of flow in the fabric treating machines with those types of textile packets in order that the distribution of the products be uniform within all the textile packet.

As we have seen, the accumulated quantity in S_i or S_e is a linear function of the treatment time, hence the smaller this time, the smaller the differences between the inner and outer zones of the textile packet. The decrease in time can only be made by changing very quickly the direction of flow of the solution, those machines which are able to do so at a higher frequency will be enabled to perform more uniform treatments or to obtain the uniformity in a shorter time.

In today's textile fabric dyeing machines provided with a pump or screw, the reversal of the direction of flow of the liquor can, at most, be done every 2 minutes for this means stopping the pump motor to change the turning direction of same, or otherwise operate a four-way valve; in both cases a time span between 2 and 5

minutes is required. By means of the machine, which is the subject of this application, the reversal may be done up to 20 four times per minute what means from 48 to 120 times as much as in the present machines, and this makes that its treatment levelling possibilities are highly superior for the distribution of the product in the inner and outer zone is made without accumulations whilst the presently used time spans for these processes may be shortened; part of these processes are used to obtain a regularization of the accumulation of the product after its being deposited on the textile fabric.

Thus, comparing the diagrams shown in FIGS. 5 and 6 it is to be seen that in the processes made in the usual apparatus (FIG. 5) the concentration C of the product increases from the inner zone (ZI) on towards the outer zone (ZE) of the textile packet during the time periods I, II, III and the levelling of this concentration is not reached before a time IV; on the other hand, by the use of the device, which is the subject of this invention, a practically equal levelling is obtained from the time I and the desired concentration is reached maintaining this levelling at a time III lower than needed in the previous case.

25 The device which is the subject of the present invention and is shown in FIG. 7, having the above mentioned principles of impelling the treatment bath through the fabric alternatingly in the one or other direction, comprises an autoclave container 1 provided with the conduits 2 and 3 with their corresponding valves 4 and 5 for the inlet and outlet, respectively, of the treatment bath, as well as a lid 6 endowed with a self sealing closing means and of a scavenger pipe 8 and a safety valve 9.

35 Inside this container 1 there is the device which impels the treatment bath through the fabric, comprising a cylinder 10 open at both its ends, having inside a piston 11 which carries out reciprocating movements which it receives from a mechanical, electric, pneumatic or hydraulic motor as in the instance shown, which consists of a cylinder 12 with its corresponding piston rod 14 connected to the corresponding piston 13 and piston rod 15 of piston 11.

40 45 One end of the cylinder 10 opens at the bottom of container 1 and the opposite end is laid out to receive a plate or base 16 acting as a sealing lid on cylinder 10, of a suitable material carrier on which are mounted the various perforated tubular supports for the textile packets. In FIG. 7 only one perforated tubular support 17 on which are piled a series of yarn bobbins 18 wound on cores 19 which are also perforated is shown; the material carrier may be adapted to any other arrangement suitable to the sort of textile packets to be treated.

55 It is easy to see that thanks to this arrangement each time that piston 11 makes an upward stroke the treatment bath contained in the upper chamber 20 of the cylinder 10 is impelled into all the perforated tubular supports 17 of the material carrier and from here through the respective packets 18 from the inside of the same towards the outside, and that, inversely, when the piston 11 makes a downward stroke the treatment bath quantity contained in the lower chamber 21 of cylinder 10 which is in communication with the rest of the treatment bath contained in container 1 through the bobbins is impelled from the outside towards the in-

side of the same and through the supporting tubes 17 again into the upper chamber 20 of cylinder 10. This amount of the treatment bath which has passed through the packets 18 is contained in said upper chamber 20 separate from the remainder of the total quantity of the treatment bath which takes the lower chamber 21 of the cylinder and of container 1.

That way, during each cycle of the reciprocating movement of piston 11 a part of the treatment bath is impelled through the yarn bobbin 18 with the same frequency as the reciprocating movement of the piston, with the possibility of varying the flowing quantity by consequently changing the piston's driving speed.

Furthermore, each chamber 20 and 21 of cylinder 10 contains independent heat exchangers made up of the worm pipes 22 and 23, respectively provided with the conduits 24 and 25 with their corresponding valves 26 and 27 to let in cold water or water steam, and the respective outlets 28 and 29 as well, with their corresponding valves 30 and 31, whereby along with the fact that the treatment bath passing through the packet 18 from the outside towards the inside is kept within the upper chamber 20 of cylinder 10 a means of conveniently controlling the temperature of this part of the treatment bath and the remaining portion of the same contained in container 1 is provided in order to be in the position to have the treatment bath circulating from the inside to the outside exactly at the same temperature as that from the outside towards the inside of the textile packet.

As has been stated before, the prime mover driving the reciprocating volumetric impelling mechanism of the treatment bath may also be of a type different from the piston type 11 described in connection with the autoclave shown in FIG. 7. Thus, in the device shown as an example in FIG. 8, said prime mover is made up of a flexible membrane 32 fastened by its outer rim to the wall cylinder 10 and by its center between the discs 33 and 34, which, in turn, are fastened to the piston rod 15 which makes a reciprocating up and down movement by means of a hydraulic motor similar to that of the device shown in FIG. 7, which is made up of the cylinder 12 and the piston rod 13. The remaining elements of this autoclave are similar to those corresponding to the autoclave of FIG. 7, for which reason the same reference numbers are being used.

In another embodiment shown in FIG. 9, the prime mover impelling the treatment bath is made up of a radial rotary pump comprising a pump body 35 instead of cylinder 10 of both foregoing embodiments, in the interior of which are mounted two blades 36 and 37 which simultaneously rotate in opposite directions, and the axes of which are mounted at the ends of a central partition 38. Both these blades 36 and 37 are mechanically coupled together by means of any suitable mechanism, for instance, each one having a sector of a gear 39, 40 which mesh with each other; one of which is conveniently joined to the end of the piston rod 14 of the piston 13 of the hydraulic driving motor, the cylinder 12 of which should be, understandably, mounted oscillateably on a suitable support 41. The remaining elements of this device in this example have also been given the same reference numbers as in the foregoing instances for they are analogous to the elements corresponding to the same.

In these three above described instances the treatment bath impelling mechanism is lodged in the interior of the container 1 of the autoclave, but it can also be located outside this container 1, what might be advantageous, for instance, in the case in which the overall height of the total assembly should be smaller.

In FIGS. 10, 11 and 12 three autoclaves corresponding to those of FIGS. 7, 8 and 9, i.e., in which the treatment bath impelling mechanism comprises a piston, a membrane pump and a radial rotary pump, respectively, are shown, but in these instances the prime movers are arranged outside the autoclave's container.

In these embodiments, a second container 43 is arranged outside the autoclave's container 42 and is in general of a smaller size, which at its top and bottom parts communicates by means of the conduits 44 and 45, with the upper part of the autoclave's container 42, and with a closed chamber 46 located in the inner and bottom part of the autoclave's container 42, respectively, the top of this closed chamber being an even lid 47 which possesses holes on which are located the drilled supports or material carriers 17 similar to those on the lid 16 of cylinder 10 and pump body 35 of FIGS. 7, 8 and 9 respectively.

Said outer container 43 comprises in its interior two heat exchangers, the top one 48 and the bottom one 49 provided with the corresponding inlet 50 and 51 and outlet 52 and 53 conduits with their pertinent valves, intended for the circulation of the heating or cooling fluids, as well as the corresponding treatment bath impelling prime mover constituted by a piston 54 in the embodiment of FIG. 10, a membrane pump 55 in the embodiment of FIG. 11 and the radial rotary pump 35 with the blades 56 in the embodiment of FIG. 12, these three treatment bath impelling mechanisms being driven by a hydraulic motor with the cylinder 57, piston 58, or by a motor of any other sort, which may indistinctively be located on the top part of the container 43, as it is shown in the figure, or in the bottom part of same.

It is to be well understood that the operation of all these devices is identical to that of the autoclave shown in FIG. 7, the sole thing which is changed is the treatment bath impelling mechanism and the structure of the prime mover of the same.

What I claim is:

1. Device for the wet treatment of packed textile materials comprising:
  - an autoclave enclosure containing a liquor for the treatment of said textile materials,
  - a plurality of perforated tubular supports for packets of said textile materials in the inside of said enclosure,
  - a space divided into first and second chambers the respective volumes of which are inversely variable, first means for communicating said first chamber of variable volume with the inside of the autoclave enclosure,
  - second means for communicating said second chamber with the inside of the perforated tubular supports on the packets of textile materials,
  - a moving part positioned within said space for the division thereof into said first and second chambers and which causes the respective volumes of said first and second chambers to vary inversely with each other,

driving means for reciprocating said moving part in the inside of said space in order to vary the volumes of said first and second chambers in an inverse ratio and to alternately impel the portion of the treatment liquor contained in said first chamber through the textile packets from the outside to the inside thereof and the portion of the treatment liquor contained in said second chamber through the textile packets from the inside to the outside thereof, and
 said first and second chambers each containing a heat exchanger provided with regulating means controllable independently from one another.

2. Device for the wet treatment of packed textile materials, comprising an autoclave enclosure containing the textile matter treatment bath; a space arranged inside said autoclave enclosure, said space being open at its bottom to freely communicate with the inside of said autoclave enclosure, and at its top said space being in communication solely with the inside of perforated tubular supports supporting textile packets which are arranged inside said autoclave enclosure; a moving part endowed with a reciprocating movement within said space which part is capable of impelling that portion of the treatment bath contained in the chamber above said moving part towards the inside of those perforated tubular supports supporting the packed textile matter and through said packed textile matter from the inside towards the outside thereof and that portion of the treatment bath contained in the chamber below said moving part into the autoclave enclosure and through the packed textile matter from the outside towards the inside thereof; and heat exchangers in each chamber, located above and underneath, respectively, said moving part in order to regulate the temperature of the respective treatment bath portion contained in those chambers above and underneath said moving part, said heat exchangers being provided with regulating means which are controllable independently from one another.

3. Device according to claim 2, wherein said moving part endowed with a reciprocating movement inside said space comprises a piston.

4. Device according to claim 2, wherein said moving part endowed with a reciprocating movement inside said space comprises a membrane pump.

5. Device according to claim 2, wherein said moving part endowed with a reciprocating movement in the inside of said space comprises radial rotary pump.

6. Device according to claim 2, wherein said part with the reciprocating movement inside said space is driven by a hydraulic motor.

7. Device for the wet treatment of packed textile materials, which comprises an autoclave enclosure containing the packed textile material treatment bath; a closed chamber located inside in the bottom part of said autoclave enclosure, the top of the closed chamber being in communication with the inside of perforated tubular supports which carry the packed textile matter; a second closed reservoir located outside said autoclave enclosure, which at its top is in communication with the upper part of said autoclave enclosure and at its bottom with the inside of said closed chamber which is located inside said autoclave enclosure; a moving part endowed with a reciprocating movement in the inside of said closed outer reservoir in order to impel with reciprocating strokes the treatment bath portion contained in the bottom part of said closed outer reservoir into that closed chamber which is located inside the autoclave enclosure and thence into the inside of perforated tubular supports which carry the packed textile matter and from the inside of said packed textile matter towards the outside thereof, and the portion of the treatment bath located in the top part of said outer closed reservoir into the inside of the autoclave enclosure and through the packed textile matter from the outside into the inside thereof and, two heat exchangers provided with independent regulating means and mounted within said outer closed reservoir above and beneath said moving part in order to separately control the temperature of the treatment bath portions lodged inside said outer closed reservoir respectively above and beneath said moving part.

8. Device according to claim 7, wherein said moving part endowed with a reciprocating movement inside said closed outer reservoir comprises a piston.

9. Device according to claim 7, wherein said moving part endowed with a reciprocating movement inside said closed outer reservoir comprises a membrane pump.

10. Device according to claim 7, wherein said moving part endowed with a reciprocating movement inside said closed outer reservoir comprises a radial rotary pump.

11. Device according to claim 7, wherein said moving part endowed with a reciprocating movement inside said closed outer reservoir comprises a hydraulic motor.
